PUMP

Arnold S. Soberg, Maywood, Ill., assignor, by direct and mesne assignments, to Sochriss Development Company, Chicago, Ill., a corporation of Illinois

Application September 11, 1946, Serial No. 696,228

9 Claims. (Cl. 103—44)

1

My invention which is particularly, but not solely applicable to deep-well pumps, has as an important objective the provision of an apparatus for pumping liquids from substantial depths which requires only hydraulic coupling between the bottom of the well and a suitable source of power on the surface thereby eliminating the necessity of long lifting rods or electrical conductors and permitting disposition of the surface power source at any convenient point either adjacent or remote from the well.

Further objects include the provision of pumping apparatus of the type described which may be economically manufactured, which is adapted for extended operation without attention, and which is applicable without difficulty to existing wells.

Briefly my pumping apparatus includes a pair of concentric pipes, the outer pipe being termed a casing and the inner being termed a piston tube. The piston tube has sealed therein a quantity of liquid which exerts a static head pressure against a pumping piston disposed within the piston tube at the bottom of the well. A power piston on the surface is employed to force the pumping piston downwardly against a spring by compressing the liquid in the piston tube. The spring returns the pumping piston to its upper position thus producing a reciprocating action which forces liquid through automatic check valves, disposed in the piston tube and in the outer casing, upwardly through the casing to a discharge pipe. The casing and discharge pipe communicate with the opposite side of the power piston and with a storage tank in such manner that the forward stroke of the power piston is utilized to force the pumping piston downwardly while the return stroke of the power piston assists in forcing liquid from the casing through the discharge pipe. This action, of course, reduces the head pressure working against the pumping piston at the bottom of the well and reduces the energy required.

Increased efficiency and reduced cost of installation may be obtained by employing a piston tube having a relatively small diameter compared to the diameter of the casing but which operates under high pressure thus reducing the mass and inertia of the reciprocated liquid.

Economy and durability are attained through the use of simply formed shapes which can be easily machined and a minimum of moving parts, particularly valves, as may be seen from the detailed description and from the drawings in which

through an upper portion of a form of my pumping apparatus;

Figure 2 is a similar section through a modified form of my apparatus;

5 Figure 3 is an enlarged sectional view of a lower portion of my invention;

Figure 4 is a vertical section through a modified form of lower portion of my apparatus;

Figure 5 is a sectional view of a modified form of lower portion of my apparatus; and

Figure 6 is a cross-sectional view taken along the lines 6—6 in Figure 5.

A basic form of my invention is illustrated in Figure 1 and includes a piston tube 10 mounted concentrically within the well casing 11 which is provided with a threaded cap 12 having a vertical opening through which the piston tube 10 may extend and a horizontal opening communicating with a pipe 13. The upper portion of the piston tube is sealed with a cap 14 and may include a priming valve 16. A power piston 17 is reciprocably mounted in sealed relation to a power piston cylinder 18, one end of which is communicating with the piston tube 10 and the other end of which is in communication with the pipe 13. A discharge pipe 19 having an automatic check valve 21 also communicates with the power piston cylinder 18 at the same end as the pipe 13 hereinafter referred to as the discharge end. A pipe 22 communicating with the discharge pipe 19 is connected to an adjustable pressure release check valve 23 which in turn communicates with the piston tube 10 adapted to relieve any excess pressure which may develop therein by discharging liquid from the piston tube 10 through the pressure release valve 23 and the pipe 22 into the discharge pipe 19.

A piston rod 24 extends through a suitable gland 26 attached to the discharge end of the power piston cylinder 18 and may be connected to a suitable source of power. The lower end of the casing 11 may be threaded to receive a pump piston assembly generally designated 27. The assembly 27 includes a cylinder 28 having an internal diameter substantially equal to the internal diameter of the piston tube 10 and adapted to be coupled thereto. The lower end of the cylinder 28 is provided with an integrally formed outwardly extending flange 29 adapted to engage the lower end of the casing 11. A pump inlet check valve 31 is mounted as by threads in the lower end of the cylinder 28 and communicates with the liquid supply outside of the casing 11. A pump outlet check valve 32 may be mounted 55 in the wall of the cylinder 28 immediately above

Figure 1 is a diagrammatic vertical section

a pump inlet check valve 31. A pump piston 33 is reciprocably mounted in the cylinder 28 and is provided with upper and lower washers 34 to prevent leakage. Preferably a stud 36 is attached to the top of the piston 33 to permit removal of the piston when necessary. One or more coil springs 37 are disposed within the cylinder 28 bearing against the bottom of the piston 33 and against a suitably disposed internal flange 38 which is preferably located immediately above the pump outlet check valve 32. A perforated well point 39 may be attached to the lower end of the casing 11 to prevent entry of debris into the pump.

In operation it is understood that the casing 11 extends downwardly from the surface of the ground to a point in or near a suitable liquid supply such as a pool of petroleum or water. Initially the piston tube 10 is filled with liquid through the priming valve 16 eliminating from the system, in so far as possible, all air. Power is then applied to the piston rod 24 reciprocating the power piston 17 within the cylinder 18. As the piston is moved forward, that is to the right as shown in Figure 1, the liquid sealed within the piston tube 10 forces the pump piston 33 downwardly compressing the coil springs 37 and driving any liquid trapped between the pump piston 33 and the pump inlet check valve 31 outwardly through the pump outlet check valve 32 into the space between the piston tube 10 and the casing 11. As the power piston 17 moves to the rear, the pressure on the liquid in the piston tube 10 is reduced causing the pump piston 33 to rise under the pressure of a compressed coil spring 37. This movement draws liquid through the well point 39 and the pump inlet check valve 31 into the cylinder 28, valve 32 being closed by the pressure of liquid in the casing or by other means such as a spring. As the pumping action continues, the casing 11 is filled with liquid causing liquid to flow through the pipe 13 and into the rear of the power piston cylinder 18. As this occurs, it may be seen that the rearward stroke of the power piston 17 will force liquid from the power piston cylinder 18 upwardly through the pipe 19 and the check valve 21 to the point of storage or use. This relieves the pump piston 33 of considerable load by reducing the head pressure working against liquid discharged into the casing 11. It is, of course, possible to connect the pipe 13 directly to the pipe 19 by passing the power piston cylinder 18 but the efficiency will be reduced. The springs 37 are selected to overcome the head pressure exerted against the piston 33 by the liquid in the piston tube 10 and in the event of marked change of temperature or other failure causing a dangerous increase of pressure in the piston tube 10, the forward stroke of the power piston 17 can drive liquid from the piston tube 10 through the pressure release valve 23 and the pipe 22 into the discharge pipe 19 after the pumping piston 33 has been forced downwardly, thereby preventing damage to the apparatus. The release valve 23 may be of any desired type such as a diaphragm valve or a balanced spring valve but in either case the valve should be adjustable to the desired maximum pressure.

I have found it desirable to use two or more coil springs 37 with the stronger spring somewhat shorter than the weaker spring but both being designed to provide a relatively long travel. In this manner a single standard set of springs can be made to operate satisfactorily in wells of varying depth where the head pressure against the

piston varies since as the load increases the lighter spring will be compressed to a point which will bring the piston into contact with the heavier spring. If it is desired to remove the lower portion of my pumping apparatus for inspection or repair, the piston 33 may be removed by inserting a suitably threaded rod through the cap 14 engaging the stud 36 thus permitting withdrawal of the piston. Removal of the cap 12 will permit removal of the entire pump piston assembly by rotation and withdrawal of the piston tube 10 which disengages the flange 29 from the casing 11. It should not, however, be understood that the assembly 27 is necessarily cast or otherwise formed in one piece since obviously it may be built up from several separately formed sections as by welding or by the use of suitably threaded connections.

In the type of pump illustrated in Figure 1, it may be seen that the volume of liquid displaced by a single stroke of the pump piston 33 is substantially equal to the liquid displaced by a single stroke of the power piston 17. This relationship, however, is not essential to the proper operation of my device and I may employ, as illustrated in Figure 2, a piston tube 41 having a diameter substantially less than that of a concentric external casing 42 or of a power piston. In this modification the forward end of the piston cylinder 18 is open and the power piston 17 is provided with a secondary piston rod 43 which is in turn connected to a secondary power piston 44 of substantially smaller diameter reciprocably mounted in a secondary power piston cylinder 46. The cylinder 46 communicates with the small piston tube 41 extending downwardly through the cap 12 to a secondary pump piston cylinder 47 which is suitably attached to the piston tube 41. Air bleed valves 48 may be provided adjacent the cap 12 and the pressure release valve 23 to assist in exhausting air from the system. In this modification a pipe 49 is provided to conduct liquid from the pressure release valve 23 to the discharge pipe 19 at a point above the check valve 21. A suitable pipe and valve connection 51 is provided interconnecting the pipe 49 with the secondary power piston cylinder 46 to facilitate priming of the system. The secondary pump cylinder 47 may be formed integrally with a threaded pump cylinder 52 (Figure 4) which engages the bottom of the casing 42, and is provided with one or more cylinder outlet valves 53 adjacent the top of a pump piston cylinder. The lower portion of the pump cylinder 52 may be provided with a well point 39 similar to that previously described. The lower end of the pump cylinder is closed as by a wall 54 except for a threaded aperture 56 in which may be mounted a pump cylinder inlet valve 57. A pump piston 58 having a diameter substantially greater than that of the piston 61 is connected by a rod 59 to a secondary pump piston 61 which is reciprocably mounted in the secondary pump cylinder 47. The pump piston 58 is provided with upper and lower washers 62 to prevent leakage and with one or more piston check valves 63 adapted to permit the upward but not downward passage of water.

The operation of this modification of my device is substantially similar to that previously described except that the priming may be accomplished by opening the air bleed valves 48 and the priming valve 51 prior to operation. This fills the piston tube 41 with liquid from the pipe 19. The pressure exerted on the liquid within the piston tube 41 is sufficiently high to force

the pump piston 58 downwardly against the pressure of one or more coil springs 37 interposed between piston 58 and the wall 54. This downward motion seats the inlet valve 57, trapping liquid between the face of the piston 58 and the wall 54. As the pressure is increased, the liquid is forced through the piston valves 63 into the space above the piston. As the power piston 17, and hence the secondary power piston 44 is retracted, the secondary pump piston 61 and pump piston 58 will rise because of the pressure exerted by the spring 37. This forces liquid through the valves 53 into the casing 42 from which it is conducted by pipe 13 to the rear or discharge end of the power piston cylinder 18 from which it is forced by piston 17 through valve 21 and pipe 19. The amount of pressure necessary to produce reciprocation of the pump piston 58 is a function of the ratio of the area of the secondary pump piston 61 to the area of the pump piston 58. For example, if this ratio is 1-10, generally the pressure relationships existing between the liquid within the piston tube 41 and the casing 42 will also be on the order of 1-10.

Figure 5 illustrates a still further modification of my device utilizing in general the same arrangement of parts illustrated and described in connection with Figures 2 and 4. In this modification, however, a pump cylinder 64 is provided with an eccentrically mounted cylindrical flange 66 threaded to engage the lower portion of the casing 42. A conduit 67 extends through the flange 66 and through a wall of the pump cylinder 64 into communication with a secondary pump cylinder 68 axially mounted within pump cylinder 64. The lower end of the pump cylinder 64 is closed as by a wall 69 apertured to receive a suitable check valve 71 adapted to permit the entry of water into the cylinder 64 but to prevent its withdrawal. Arms 72 may extend from a secondary pump cylinder 68 to the wall 69 providing supporting means for the former. The flange 66 extends inwardly over the upper end of the pump cylinder 64 and is provided with a cylinder outlet valve 72 communicating with the casing 42. A pump piston 73 having one or more check valves 74, mounted in conduits extending through the pistons, is reciprocably mounted in the pump cylinder 64 and may be provided with suitable washers 76. A rod 77 connects the pump piston to a secondary pump piston 78 which is substantially smaller in diameter than the pump piston 73. The valves 74 in the piston 73 are adapted to permit liquid to pass upwardly through the piston but to prevent its flow in a reverse direction. One or more coil springs 37 are interposed between the head of the piston 73 and the flange 66. Since the conduit 67 communicates with the piston tube 41, it may be seen that as the pressure within the piston tube is increased, the secondary pump piston 78 will rise forcing the piston 73 upwardly and driving liquid upwardly through the outlet check valve 72 into the casing 42. As the pressure within the piston tube 41 is released, the spring 37 will force the piston 73 downwardly thus permitting liquid trapped in the cylinder 64 between the wall 69 and the piston 73 to pass through the piston into the pump chamber. The upward stroke of the piston 73 also draws liquid into the cylinder 64 through the inlet check valve 71. In this modification, since the piston tube 41 is not concentric with the casing, it is desirable to provide a centrally disposed stud 79

fixed to the flange 66 to permit withdrawal of the lower portion of my device from the well.

Of the valves herein described, only the cylinder inlet and outlet check valves are essential, as, for example, valves 31 and 32 in Figures 1 and 3, or valves 57 and 63 in Figures 2 and 4, the other valves being desirable to increase efficiency and ease of operation.

From the foregoing description, it is obvious that no lifting rods are required to operate my pump and since the power is transmitted from the surface to a pumping piston at the bottom of the well hydraulically, the power source may be located at any convenient point adjacent to or remote from the well. Since synchronism is automatic, a single power piston may, by suitable manifold corrections, be made to operate a plurality of wells.

Substantially all of the component parts required and essential to the operation of my apparatus may be simply formed of inexpensive materials by standard low cost machining or casting operations and since the moving parts required for the operation of my device are few, it may be seen that the potential sources of wear or malfunctioning are reduced to a minimum.

The foregoing description has been made with the knowledge that those skilled in the art may make many substitutions and modifications of the precise arrangement and disposition of parts herein described by way of illustration, and I do not therefore limit myself to the specific details herein described except in so far as defined by the appended claims.

I claim:

1. Pump apparatus comprising a power cylinder, a substantially vertical pump cylinder disposed adjacent the source of liquid, a secondary cylinder adjacent the pump cylinder, a liquid-filled piston tube interconnecting one end of the power cylinder with the secondary cylinder, a casing around the piston tube, a discharge conduit communicating with the casing, a check valve in the discharge conduit, a power piston reciprocably mounted in the power cylinder, a secondary power piston mounted reciprocably in the secondary cylinder, a pump piston reciprocably mounted in the pump cylinder defining therewith a pump chamber and rigidly connected to said secondary power piston, a conduit through said pump piston, a valve controlling said conduit, a spring in the pump cylinder disposed to resist movement of the pump piston in one direction, an inlet check valve in the bottom of the cylinder, and an outlet check valve between the pump chamber and the casing.

2. Pumping apparatus comprising a power cylinder, a substantially vertical pump cylinder adjacent a source of liquid, a secondary power cylinder adjacent said pump cylinder, a liquid-filled piston tube interconnecting one end of the power cylinder with the secondary cylinder, a casing around the piston tube communicating with the other end of the power cylinder, a discharge conduit communicating with the power cylinder, a check valve in the discharge conduit, a power piston reciprocably mounted in the power cylinder, a pump piston reciprocably mounted in the pump cylinder defining therewith a pump chamber, a secondary power piston reciprocably mounted in the secondary cylinder and connected to said pump piston, a spring in the pump cylinder disposed to resist movement of the piston in one direction, an inlet check valve between the pump chamber and the source of liquid, and

an outlet check valve between the pump chamber and the casing.

3. Pumping apparatus adapted for use in conjunction with a well casing and a liquid-filled piston tube comprising a pump cylinder, a piston in the cylinder defining therewith a pump chamber, an inlet check valve for the chamber, an outlet check valve between the chamber and the casing, spring means on one side of the piston opposing movement of the piston in one direction, a secondary piston connected to the pump piston, a cylinder around the secondary piston communicating with one end of the piston tube, the diameter of the secondary piston being substantially less than the pump piston, and means for varying the pressure of the liquid in the piston tube comprising a power piston reciprocably mounted in a cylinder connected with the other end of the piston tube.

4. Pumping apparatus adapted for use in conjunction with a well having a casing and a liquid-filled piston tube comprising a pump cylinder, a pump piston in the cylinder defining a pump chamber, said piston having a conduit extending therethrough, a check valve in the conduit, a cylinder inlet check valve below the piston, a cylinder outlet check valve above the piston, communicating directly with the casing, a spring at one side of the pump piston resiliently opposing movement of the piston in one direction, a secondary piston rigidly connected to the pump piston on the other side of the pump piston, a cylinder around the secondary piston communicating with the piston tube, the diameter of the secondary piston being substantially smaller than the pump piston, said secondary piston sealing said piston tube from communication with said pump chamber and means for varying the pressure of the liquid within the piston tube.

5. Pumping apparatus adapted for use in conjunction with a well having a casing and a liquid-filled piston tube comprising a pump cylinder, a piston in the cylinder defining a pump chamber, said piston having a conduit extending therethrough, a check valve in the conduit, a cylinder inlet check valve below the piston, a cylinder outlet check valve above the piston communicating directly with the casing, a spring at one side of the piston resiliently opposing movement of the piston in one direction, a secondary piston rigidly connected to the pump piston at the other side, a cylinder around the secondary piston communicating with one end of the piston tube to seal it from the pump chamber, the diameter of the secondary piston being substantially smaller than the pump piston, means for varying the pressure of the liquid within the piston tube comprising a cylinder connected to the other end of the piston tube and a reciprocating piston therein, and means for releasing pressure developed in the piston tube in excess of the predetermined value comprising a pressure release valve in said piston tube.

6. Pumping apparatus adapted for use in conjunction with a well having a casing and a liquid-filled piston tube comprising a pump cylinder, a piston in the cylinder defining a pump chamber, said piston having a conduit extending therethrough, a check valve in the conduit, a cylinder outlet check valve, above the piston, communicating directly with the casing, a spring at one side of the piston resiliently opposing movement of the piston in one direction, a secondary piston rigidly connected to the pump piston on the other side, a cylinder housing the secondary piston

communicating with one end of the piston tube to seal it from the pump chamber, the diameter of the secondary piston being substantially smaller than the pump piston, means for periodically increasing the pressure of the liquid within the piston tube to move the pump piston against the spring resistance, a pressure release valve in said piston tube and a valved conduit connecting said piston tube with a supply of liquid, to provide means for replenishing liquid in the piston tube.

5 7. Pump apparatus comprising a power cylinder, a substantially vertical pump cylinder disposed adjacent the source of liquid, a liquid-filled piston tube connected with one end of the power cylinder, a relief valve for relieving pressure in the piston tube in excess of the predetermined value, a casing around the piston tube, a discharge conduit communicating with the casing, a check valve in the discharge conduit, a secondary power cylinder adjacent the pump cylinder and connected with said piston tube, a power piston reciprocably mounted in the power cylinder, a pump piston reciprocably mounted in the pump cylinder defining therewith a pump chamber, a secondary power piston in the secondary cylinder connected with the pump piston and sealing said piston tube from the casing, a spring in the pump cylinder disposed to resist movement of the piston in one direction, an inlet check valve in the cylinder below the piston, and an outlet check valve between the pump chamber and the casing, said power piston adapted to periodically increase the pressure in the piston tube to move the secondary piston against the spring action.

30 8. Pumping apparatus adapted for use in a well having a casing comprising a liquid-filled piston tube, a pump cylinder, a pump piston in the cylinder having a conduit, a check valve in the conduit, a secondary cylinder below the piston communicating at one end with the piston tube, a power piston in the secondary pump piston cylinder, means rigidly connecting said pistons, a cylinder inlet check valve below the power piston, a cylinder outlet check valve above the pump piston communicating directly with the casing, a spring in the pump cylinder disposed to resiliently resist movement of the pistons in one direction, and means for periodically increasing the pressure of the liquid in the piston tube to move the power piston against the spring action whereby the spring and liquid pressure combine to reciprocate the power piston to pump liquid from the pump cylinder directly to the pump casing.

45 9. Pumping apparatus adapted for use in a well having a casing comprising a liquid-filled piston tube, a pump cylinder, a pump piston in the cylinder having a conduit, a check valve in the conduit, a secondary cylinder below the piston communicating at its lower end with the piston tube, a power piston in the secondary cylinder, means rigidly connecting said pistons, a pump cylinder inlet check valve below the power piston, a pump cylinder outlet check valve about the pump piston communicating with the casing, a spring in the cylinder disposed to resiliently resist upward movement of both pistons, a discharge pipe connected to the casing, a check valve in the discharge pipe, and single means for varying the pressure of liquid in the piston tube and in the casing comprising two concentric cylinders of different sizes, the smaller being connected with the liquid-filled piston tube, the larger connected with the discharge pipe, interconnected pistons in each of said cylinders and means for reciprocating said pistons, whereby the outer stroke of

the smaller will transmit pressure through the piston tube to move the power piston upwardly.
